UNITED STATES PATENT OFFICE

143,098

DESIGN FOR A HOUSING FOR THRESHING AND SEPARATING MECHANISM OF A HAR- VESTER-THRESHER

Charles J. Scranton, La Porte, Ind.

Application February 28, 1945, Serial No. 118,189

Term of patent 14 years

(Cl. D40—1)

To all whom it may concern:

Be it known that Charles J. Scranton, a citizen of the United States, residing at La Porte, in the county of La Porte and State of Indiana, has invented a certain new, original, and ornamental Design for a Housing for Threshing and Separating Mechanism of a Harvester-Thresher, of which the following is a specification, reference being had to the accompanying drawings, forming part thereof.

In the accompanying drawings:

Fig. 1 is a front perspective view of a housing

for threshing and separating mechanism of a harvester-thresher, showing my new design;

Fig. 2 is another front perspective view of the design shown in Fig. 1; and

Fig. 3 is a rear perspective view of the design shown in Fig. 1.

I claim:

The ornamental design for a housing for threshing and separating mechanism of a harvester-thresher, as shown.

CHARLES J. SCRANTON.
